UNITED STATES PATENT OFFICE.

ERNEST D. WHIDDEN, OF POMONA, CALIFORNIA.

HOT-AIR FURNACE.

Application filed October 22, 1925. Serial No. 64,209.

This invention aims to provide a heater for buildings, which will be inexpensive to manufacture and compact in form, novel means being provided for conducting and carrying for the products of combustion, and novel means being provided whereby air may be delivered about the radiator, to be heated.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in vertical section, a device constructed in accordance with the invention, parts being in elevation; Figure 2 is a sectional detail view of one of the valves; Figure 3 is a section taken horizontally, about on the line 3—3 of Figure 1; Figure 4 is a section taken about on the line 4—4 of Figure 1, the casing being indicated diagrammatically.

The numeral 1 marks the floor of a building, and below the floor is disposed a casing 2 which is closed at its lower end, a grating or register 3 being mounted on the floor 1 and extending across the upper end of the casing 2, the grating 3 having a movable section 4. Fresh air may be supplied to the casing 2 in any desired way, for instance, by means of a pipe 5 communicating at its lower end with the casing 2 near to the bottom of the casing, and extended at its upper end through the floor 1, at some distance from the casing 2, as shown in Figure 1.

Partly supported at 6 within the casing 2 is a radiator, which is denoted generally by the numeral 7, the radiator comprising end plates 8 and elongated tubes 10 mounted at their ends in the plates 8 and opening through the said plates. The plates 8 are united by connections 11. At one end, the tubes 10 communicate with a header 12 mounted on one of the end plates 8. At their opposite ends, the tubes 10 communi-

cate with a header 14 mounted on the corresponding end plate. The end plates 8 of the radiator 7, and the headers 12 and 14, extend downwardly below the tubes 10, as shown in Figure 1. An outlet 15 for the products of combustion communicate with the lower portion of the header 14 and discharges outwardly through one end of the casing 2.

A plurality of horizontally aligned flues 16 are mounted at their outer ends on the lower portion of one of the end plates 8 and communicate with the lower portion of the header 12. At their inner ends, the flues 16 communicate with the transverse head 17 of a vertical heater 18 supported on the bottom of the casing 2. Within the heater 18, at the lower end thereof, are located burners 19 communicating with a lower manifold 20 to which leads a horizontal pipe 21 disposed below the bottom of the casing 2. The pipe 21 has a flared end 23. A nozzle 24 discharges into the flared end 23 of the pipe 21, the nozzle 24 being carried by a coupling 25, the nozzle having an internal seat 26, with which cooperates a valve 27, the valve being threaded into the coupling 25, and being connected by a universal joint 28 with an inclined shaft 29, the shaft 29 extending upwardly into the casing 2, and being connected by a universal joint 30 with a vertical shaft 31 supported for rotation in the grating or register 3, and adapted, at its upper end, to be operated by a removable key 32, or in any other desired way. Fuel is supplied to the coupling 25 through a pipe 33 located below the casing 2, a rotatable valve 35 being interposed in the pipe 33, the valve having an arm 36 to which is pivoted an upwardly extended connection 37, the upper end of the connection 37 being pivoted to a lever 38 fulcrumed at 39 on the casing 2 and located within the casing, the lever being accessible through the grating or register 3, and having a socket 40, into which a nail or other object may be inserted, to bring about a swinging of the lever 38. A lighting tube 42 extends downwardly through the radiator 7 and communicates at its lower end with the transverse head 17 of the heater 18, the tube 42 being surmounted by a removable cap 43 which is accessible when the movable section 4 of the register 3 is opened.

In practical operation, the fuel flows

2

through the pipe 33, under the control of the valve 35, the valve being operated by a train of elements including the arm 36, the connection 37 and the lever 38. A fine adjustment in the amount of fuel delivered to the nozzle 24 is secured by means of the valve 27, it being possible to adjust the position of the valve 27 with respect to the seat 26, by rotating the valve through the instrumentality of the shaft 29, the shaft 31, and the key 32. The fuel is discharged from the nozzle 24 into the flared end 23 of the pipe 21, air entering the pipe 21 through the flared end 23, the mixture passing to the burners 19. By opening the section 4 of the grating 3, and by removing the cap 43, the fuel may be ignited at the burners 19, through the tube 42, by means of a torch, or by means of a match dropped downwardly through the tube 42. The products of combustion pass upwardly into the head 17 of the heater 18 and proceeds, by way of the flues 16, into the lower portion of the header 12. The products of combustion pass upwardly in the header 12, and, thence, move through the tubes 10, the products of combustion passing from the tubes 10 into the header 14, and leaving by way of the outlet 15. The tubes 10 of the radiator 7 are heated, and the air within the casing 2 is heated, the air rising through the grating or

register 3, the air being supplied to the casing 2 by way of the pipe 5.

The air within the casing 2 is heated not only by the radiator 7, but is heated, also, 35 because the heater 18 is located within the casing.

What is claimed is:—

In a device of the class described, a casing having an outlet opening, means for admitting air to the casing, a radiator in the casing and including spaced vertical headers and horizontal tubes connecting the headers, the vertical transverse dimension of each tube being materially greater than its horizontal transverse dimension, the tubes being disposed in a single horizontal row, the headers comprising depending parts prolonged downwardly below the tubes, the depending part of one header being supplied with an outlet, a heater in the casing, and extended upwardly between the depending parts of the headers, and a plurality of flues, located in approximate horizontal alignment and disposed below the tubes, the flues communicating with the upper portion of the heater and with the depending part of the other header.

In testimony that I claim the foregoing as my own, I have hereto affixed my signature.

ERNEST D. WHIDDEN,
